UNITED STATES PATENT OFFICE.

HAROLD G. WARE, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed March 15, 1928. Serial No. 261,811.

My invention relates to rail anchors of the general type having a member for gripping one flange of a rail base and a retaining bar extending across beneath the rail base and engaging the opposite edge thereof to lock the gripping member on the rail.

The principal object of the invention is to provide an improved two-piece anchor of the above general type in which the cross bar and gripping members are so formed and engaged with each other as to insure engagement of the bar with the opposite edge of the rail base when the anchor is applied. In this connection the invention contemplates the provision of a cross bar which is so formed as to pivot on the gripping member at a point between the longitudinal edges of the rail base and adapted to be wedged between the gripping member and said bottom surface of the rail base; whereby the pressure against the top surface of the bar near one end thereof tends to swing the other end upwardly and hold it in engagement with the vertical edge of the rail base at the opposite side of the rail.

Another object of the invention is to provide an improved rail anchor of the above general type in which the retaining member is distorted during the application of the device to exert a resilient grip vertically of the rail base, the said bar being so formed as to provide a firm frictional contact with the bottom surface of the rail base at the edge thereof. In anchors of the general type to which the present invention appertains, the portion of the cross bar intervening between the bottom surface of the rail base and the gripping member does not provide sufficient bearing surface to hold the hooked end of the bar in engagement with the edge of the rail base under all conditions of service. This condition is emphasized in situations in which the jaw gripping member does not fit tightly against the bottom surface of the rail base, for example, when the bottom surface of the rail base, due to inaccuracy in its manufacture, is slightly convex near the longitudinal edge thereof, or when the base flange of the rail is thinned near the edge by corrosion or other service conditions tending to wear away the under surface of the rail base near the edge thereof. The present invention contemplates a device which will so grip the rail base as to overcome the

above mentioned and other incidental objections to anchors of the above general type, heretofore used or proposed.

Another and more specific object of the invention is to provide a retaining member which will have a wedging engagement between the bottom surface of the rail base and a portion of the rail gripping member so as to function in the manner above stated and at the same time permit either end of the retaining member to be engaged with the rail gripping member when such reversal of its position is desired.

The preferred embodiment of the invention is illustrated in the accompanying drawings, wherein

Fig. 1 is a side view of a rail anchor constructed in accordance with my invention, shown in its initial position on a rail and before pressure is applied to the gripping member to force it transversely of the rail.

Fig. 2 is a side view of the embodiment shown in Fig. 1, but illustrating the anchor in a position which it assumes after the gripping member has been driven transversely of the rail, but before the anchor has reached its final operative position.

Fig. 3 is another side view of the rail anchor showing it in its normally applied position on the base flange of a rail.

Fig. 4 is an end view of the anchor illustrating the effect of certain stresses on the anchor during its application to the rail.

Fig. 5 is a view in perspective of the gripping member, and

Fig. 6 is a view in perspective of the retaining member.

In the preferred embodiment of the invention, the anchor is made of two separately formed members, a rail gripping member 10 and a retaining member 11. The gripping member is made from a metal strip formed with recesses 12 and 13 and bent to the configuration shown in Fig. 5, so as to provide upstanding jaw portions 14 and 15 adapted to be driven into gripping engagement with the top and bottom surfaces of the rail base. The jaw portions 14 and 15 are spaced from each other longitudinally of the rail and are held in spaced relation to each other by means of the upwardly projecting seat portion 16. The recesses 12 and 13 are formed so as to fit tightly on the rail. Preferably the lower jaws 17, 18 of the gripping member are so positioned

with relation to the upper surface 19 of the intermediate portion 16 as to provide a space between the upper surface 19 and the bottom surface of the rail base. Preferably this space is greater than the thickness of the cross-bar retaining member 11 so that when the gripping member is driven onto the rail the offset portion will not be entirely flattened out. The downward pressure in addition to flexing the offset end will be exerted on the intermediate portion 16 so as to flex the bends 20, 21 in the manner indicated in dotted lines in Fig. 4. This flexing of the bends 20, 21, tends to spread the lower ends of the jaws 14, 15 so that the said jaw portions 14 and 15 will normally stand at oblique angles to the bottom surface of the rail and thereby exert a shackle grip on the top and bottom surfaces of the rail base. The bends 20 and 21 are preferably formed with a relatively small radius so as to provide a construction that is relatively rigid transversely of the rail, but which, nevertheless, will permit some yielding transversely of the rail, as will be noted by comparison of Figs. 2 and 3. Preferably the intermediate portion 16 of the gripping member is normally in alignment with the jaw portions when the anchor is free of the rail, but when in its fully applied position, the intermediate member is forced to a slightly angular position, shown in Fig. 3, relative to the jaw, so as to exert a spring grip transversely of the rail.

The retaining member 11 consists of a flat strip of metal adapted to fit in the space between the jaws 14 and 15 of the gripping member. The width of the metal strip is such that it is necessary to spring the jaws apart slightly to insert the retaining member between them, whereby the retaining member is held in its engagement with the gripping member by the resiliency of the jaws. The ends of the member 11 are bent at right angles to the body, in opposite directions, so as to provide flanges 22 and 23. The flange 22, in the assembly illustrated in the drawings, engages the outer edge of the portion 16 of the gripping member and the upstanding flange 23 engages the edge of the rail base at the opposite side of the rail. In order to hold the flange 23 in its intended position (Fig. 3), I preferably form the bar 11 with an offset bend 24 so as to provide a fulcrum point 25 (Fig. 1), about which the member 11 will rock when the anchor is driven to its applied position. The offset portion 24 in addition to providing a rocking axis 25 extending longitudinally of the rail, provides a wedge-shaped upper surface 26, which may be driven into tight frictional grip with the bottom surface of the rail. The offset bend, in addition to providing a firm grip of the anchor on rails having base flanges of perfect cross-section, provides a resilient wedge construction which insures a firm bearing of the retaining member against the bot-

tom surface of a rail base when the said bottom surface is worn or corroded in such manner as to form a curved or inclined surface near the edge of the base flange. The other end of the retaining bar 11 is formed with a similar off-set bend 27 so that the bar 11 may at any time be reversed and the offset end 27 fitted between the jaws 14 and 15 of the gripping member. The length of the bar 11 is preferably such that when the jaws of the gripping member are in their fully applied position, as shown in Fig. 3, it is necessary to force the intermediate portion 16 of the gripping member to a slight angular position relative to the jaws 14 and 15 to provide the necessary movement of the bar 11 to permit the flange 23 to snap over the edge of the rail base (Fig. 3.) This distortion of the portion 16 of the gripping member may be effected in any suitable or preferred manner, as by striking the downturned end 22 of the bar 11, so as to force it transversely of the rail base.

In operation, either end of the retaining member 11 may be positioned between the jaws 14 and 15 of the gripping member so as to bear at the points 25, 25^a (Fig. 1) on the intermediate portion 16 of the gripping member. When in this position the offset 24 stands slightly above the lower jaws 17, 18 of the gripping member. The anchor device may be applied to its initial position, (Fig. 1) by hand. The downturned end 22 may then be struck with a suitable implement to drive the gripping member and the retaining member transversely of the rail until the gripping jaws have been forced to their rail gripping position, as shown in Fig. 2. During this transverse movement of the gripping member and retaining member, the offset portion 24 of the retaining member is depressed by engagement with the bottom surface of the rail base so as to rock the retaining member 11 about the fulcrum point 25 and thereby urge the end 23 of the member 11 upwardly. When the gripping member has been driven to the applied position, as shown in Fig. 2, the upstanding flange 23 at the opposite end of the rail, preferably stands slightly below the edge of the rail. By the application of further force against the downturned flange 22, the intermediate portion 16 of the gripping member is distorted sufficiently to permit the flange 23 to snap over the edge of the rail base and thereby lock the gripping member in its applied position. The offset end 24 of the member 11, being forced between the portion 16 of the gripping member and the bottom surface of the rail is partly flattened out and exerts a firm grip against the bottom surface of the rail base regardless of the contour of the base and by reason of the pivotal action at the point 25 will hold the flange 23 in its locking position adjacent the opposite edge of the rail base. The pressure against

the bottom surface of the rail base, in addition to distorting the offset bend 24, will also effect some slight distortion of the bends 20, 21 so as to move the jaw portions 14 and 15 5 to a slightly oblique position on the rail base, so as to bring the rail gripping jaws into shackle gripping engagement with the top and bottom surfaces of the rail base. This flexing action is illustrated in Fig. 4, where- 10 in the dotted lines illustrate the normal position of the jaws and bends 20, 21 when the anchor is free of the rail, the full lines illustrating the positions assumed by the jaws when driven to rail-gripping position.

15 While I have illustrated my invention in connection with one specific embodiment, it will be obvious to those skilled in the art that like results may be obtained by other constructions. It will be understood, therefore, 20 that I do not wish to limit myself to the exact constructions shown and described except in so far as specific limitations appear in the claims which follow.

I claim:

25 1. A rail anchor comprising a rail gripping member and a retaining member engaged therewith and adapted to engage an edge of the rail base to lock the gripping member in its applied position; one end of 30 said retaining member having a pivotal bearing on the gripping member and adapted to be stressed by engagement with the rail base to urge the other end of the retaining member upwardly into engagement with the rail.

35 2. A rail anchor comprising a rail gripping member and a retaining member engaged therewith and adapted to engage one edge of the rail base to lock the gripping member in its applied position; one end portion 40 of said retaining member having a pivotal bearing on the gripping member and adapted to be rocked by engagement with the rail base to urge the other end of the retaining member upwardly into locking engagement with the vertical edge of the rail base.

45 3. A rail anchor comprising a rail gripping member and a retaining member engaged therewith and adapted to engage one edge of the rail base to lock the gripping member in its applied position; one end portion 50 of said retaining member being formed to provide a pivotal bearing against the gripping member and adapted to be rocked by engagement with the rail base to urge the other end of the retaining member upwardly 55 into engagement with the rail.

60 4. A rail anchor comprising a rail gripping member and a retaining member engaged therewith and adapted to engage an edge of the rail base to lock the gripping member in its applied position; one end of 65 said retaining member being formed to provide a pivotal bearing at a point beneath the base of the rail and to form a portion at one side of said bearing adapted to be engaged

by the rail base, whereby movement of the anchor to its applied position stresses said retaining member adjacent said bearing and urges the free end thereof upwardly into locking engagement with the opposite side 70 of the rail base.

5. A rail anchor comprising a rail gripping member and a retaining member engaged therewith and adapted to engage the edge of the rail base to lock the gripping member in its applied position; one end portion of said retaining member being formed with an offset portion providing a clearance between said end and the gripping member and adapted to be forced into binding engagement between the rail base and the gripping member. 80

6. A rail anchor comprising a rail gripping member for engagement with the rail base at one side of a rail and a retaining member for engagement with the gripping member and the opposite side of the rail to lock the gripping member in its applied position; the retaining member being formed at one end with an offset adapted to be forced between the bottom surface of the rail base and a substantially horizontal portion of said gripping member to urge the other end of the retaining member upwardly into locking position. 95

7. A rail anchor comprising a rail gripping member for engagement with a rail base at one side of a rail and a retaining member for engagement with the gripping member and the opposite side of the rail to lock the gripping member in its applied position; the retaining member being formed at one end with a wedge surface adapted to be forced into binding engagement between the bottom surface of the rail and a substantially horizontal portion of said gripping member. 100

8. A rail anchor comprising a rail gripping member for engagement with a rail base at one side of a rail and a retaining member for engagement with the gripping member and the opposite side of the rail to lock the gripping member in its applied position; the retaining member being formed at one end with an offset to provide a resilient wedge portion adapted to be forced into binding engagement between the bottom surface of the rail and a substantially horizontal portion of said gripping member. 110

9. A rail anchor comprising a rail gripping member for engagement with the rail base at one side of a rail and a retaining member for engaging the gripping member and the opposite side of the rail to lock the gripping member in its applied position; the retaining member being formed at its ends with portions offset in opposite directions, either of which offset portion is adapted to be forced into binding engagement between the bottom surface of the rail and a portion of said gripping member to effect a resilient 120

125

130

grip on the bottom surface of the rail and to hold the free end of the retaining member up in locking position.

10. A rail anchor comprising a rail gripping member for engagement with a rail base at one side of a rail and a retaining member formed at opposite ends with angularly disposed portions for engagement with the rail gripping member and the opposite side of the rail to lock the gripping member in its applied position; the said retaining member being formed near its ends with offset portions either of which is adapted to be positioned between said jaws and provide a pivotal bearing surface on a part of said gripping member, whereby movement of the gripping member to its applied position simultaneously with the movement of the retaining member transversely of the rail subjects the retaining member to a stress tending to urge the free end thereof upwardly into locking engagement with the rail base.

11. A rail anchor comprising a rail gripping member and a retaining member engaged therewith and adapted to engage an edge of the rail base to lock the gripping member in its applied position; one end portion of said retaining member being formed with a bend, the bent portion of which provides clearance between the retaining member and a subjacent portion of the gripping member and is engaged by the base flange of the rail during the application of the device to a rail, whereby movement of the anchor to its applied position distorts said bend to reduce said clearance.

12. A rail anchor comprising a rail gripping member provided with spaced jaw portions for gripping one flange of a rail base and provided intermediate said jaw portions with an upwardly projecting seat portion, and a transverse bar positioned between said jaws and in engagement with the intermediate portion and formed to engage the opposite edge of the rail base to lock the gripping member in its applied position; the said retaining member being formed at its ends with portions offset in opposite directions, either of which portion provides a resilient wedge adapted to assume a position between the bottom surface of the rail and said upwardly projecting portion of the gripping member when the gripping member is driven to its applied position.

13. A rail anchor comprising a rail grip-

ping member provided with spaced jaw portions for gripping one flange of a rail base and provided intermediate said jaw portions with an upwardly projecting seat portion, and a transverse bar positioned between said jaws and in engagement with the intermediate portion and formed to engage the opposite edge of the rail base to lock the gripping member in its applied position; the said retaining member being formed at its ends with portions offset in opposite directions, either of which portion provides a resilient wedge adapted to assume a position between the bottom surface of the rail and said upwardly projecting portion of the gripping member when the gripping member is driven to its applied position, the length of said retaining member being normally such that it is necessary to flex said intermediate portion of the gripping member transversely of the rail to permit the retaining member to spring into locking engagement with the rail base.

14. A rail anchor comprising a member provided with spaced jaw portions for engaging one flange of a rail and an intermediate portion extending under the base of the rail, a transverse bar for engagement with the opposite edge of the rail base provided with an offset end portion supported on said intermediate portion of the gripping member and adapted to be pressed downwardly when the anchor device is moved to its applied position.

15. A rail anchor comprising a member provided with spaced jaw portions for engaging one flange of a rail and an intermediate portion extending under the base of the rail, a transverse bar for engagement with the opposite edge of the rail base formed at each end with an offset portion, either of which is adapted to be supported on said intermediate portion of the gripping member and retained in its normal position by a spring pressure exerted by said jaw portion, the form of said offset portions being such that the end of the retaining member interposed between the rail base and the intermediate portion of the gripping member is depressed by application of the anchor to a rail so as to exert vertical spring pressure against the bottom surface of the rail and to urge the opposite end of the retaining member upwardly into locking engagement with the base flange of a rail.

HAROLD G. WARR.
